LOCK

Stephen F. Briggs, Chenequa, Wis., assignor to
 Briggs & Stratton Corporation, Milwaukee,
 Wis., a corporation of Delaware

Application April 7, 1933. Serial No. 664,857

8 Claims. (Cl. 70—29)

This invention relates to certain new and useful improvements in locks, and refers more particularly to locks especially adapted for use with compartment doors and especially the doors 5 of instrument board compartments of automobiles.

It is an object of this invention to provide a simple lock device for securing compartment doors and the like closed, in which part of the 10 lock assembly provides a handle to facilitate opening and closing of the door.

Another object of this invention is to provide a lock device of the character described, embodying a spring latch adapted to hold the door 15 closed with spring tension and in which means are provided to hold the spring latch against movement necessary to enable opening of the door.

And a further object of this invention is to 20 provide a lock device of the character described which is composed of but a few readily assembled parts.

With the above and other objects in view which will appear as the description proceeds, 25 my invention resides in the novel construction, combination and arrangement of parts substantially as hereinafter described and more particularly defined by the appended claims, it being understood that such changes in the precise 30 embodiment of the hereindisclosed invention may be made as come within the scope of the claims.

In the accompanying drawing, I have illustrated one complete example of the physical 35 embodiment of my invention constructed according to the best mode I have so far devised for the practical application of the principles thereof, and in which:

Figure 1 is a vertical section through a compartment door of an automobile instrument board equipped with the lock mechanism of this 40 invention; and

Figure 2 is a back view of the lock mechanism per se, taken on the plane of the line 2—2 45 of Figure 1.

Referring now more particularly to the accompanying drawing in which like numerals indicate like parts throughout the several views, the numeral 5 represents the front wall of the 50 compartment which may be, as in the present instance, part of the instrument board of an automobile.

A door 6 is hingedly mounted as at 7 to swing 55 to and from a position closing the entrance to the compartment formed by an opening in the wall 5. The hinged connection 7 is so designed that when the door is closed, the entire hinge is concealed.

60 The door 6 is hollow, being composed of an

outer wall 8 and an inner wall 9 connected adjacent the peripheral edge portions of the door. Within the space between the outer and inner wall is the bolt and latching mechanism of this invention, indicated generally by the numeral 10, 65 and by which the door may be secured in its closed position.

The latching mechanism comprises a spring latch element 11 formed from a single piece of spring sheet metal with a flat attaching portion 70 12 and a spring finger 13 projecting therefrom for engagement with the adjacent edge 14 of the opening closed by the door. The outer extremity of the finger 13 is curved as shown to facilitate engagement and disengagement thereof with the 75 edge 14 as the door is closed and opened.

The spring latch element is mounted with its spring finger extending through an opening 15 in the upper wall connecting the outer and inner walls of the door and is mounted on the door 80 with its attaching portion 12 in flat engagement with the inner face of the outer wall 8. It is retained in this position by a tubular knob 16, which has a threaded end 17 of reduced diameter passing through aligned openings 18 and 19 85 in the wall 8 and portion 12, respectively.

The threaded end portion 17 of the knob has a flat side 20 and the openings 18 and 19 are correspondingly provided with flat sides to preclude relative rotation between the knob and 90 the door and to hold the spring latch element against turning.

A nut 21 threaded on the portion 17 clamps the peripheral edge portions of the wall 8 and the spring latch element between it and a 95 shoulder 22 formed at the base of the threaded portion 17 by the enlarged outer end of the knob.

The knob 16, as stated, is tubular and besides 100 having the function of a handle to facilitate opening and closing of the door, it affords a casing for a lock cylinder 23 rotatably mounted therein. The lock cylinder 23, as is customary, is provided with the usual tumblers which are spring urged to secure the cylinder against rotation and are retractable upon the insertion of a proper key 24 to free the lock cylinder for rotation.

At its inner end, the lock cylinder has a bolt 110 25 fixed thereto, which is adapted to be swung up through the opening 15 into engagement with the outer end portion 13 of the spring latch element.

As best illustrated in Figure 2, the outer end 115 of the bolt 25 is stepped as at 26 and is shaped to enable it to project up into and under the curved outer end portion 13 of the spring latch element to hold the same against movement to an inoperative position. The bolt 25 not only holds the outer end of the spring latch element 120

firmly in engagement with the adjacent edge portion 14, but also has a substantial portion thereof projecting above the edge 14 to positively preclude opening of the door when in its 5 locked position.

Obviously, to release the door for opening, it is necessary to turn the lock cylinder by means of its key 24 at least a sufficient distance to carry the outer end of the bolt 25 beneath the 10 edge 14, but preferably to the dotted line position shown in Figure 2, which is defined by the engagement of the edge 27 of the bolt with a pin 28 carried by the adjacent end of the knob or casing member.

15 From the foregoing description taken in connection with the accompanying drawing, it will be readily apparent to those skilled in the art to which this invention appertains, that this invention, by reason of its novel combination 20 of a spring latch and a positive lock, affords an extremely simple and efficient locking mechanism for compartment doors and particularly the doors of instrument board compartments in automobiles.

25 What I claim as my invention is:

1. A lock device of the character described comprising, a bored member, a spring latch element comprising a sheet of spring metal having a flat attaching portion and a spring finger projecting therefrom, common means to mount the bored member and said spring latch element, a key operable lock cylinder within the bored member, and a locking bolt carried by the lock cylinder and adapted to swing into engagement 30 with the spring finger to retain the same in an operative position.

2. A lock device of the character described comprising, a bored handle knob adapted to be attached to a member to be moved, a spring 40 latch element, common means to hold the handle knob and the spring latch element to said member to be moved, said spring latch element having a finger engageable with a fixed abutment to yieldably hold said member in a predetermined position, a key operable lock cylinder in the bore of the handle knob, and a locking bolt carried by the lock cylinder and engageable with the finger of the spring latch 45 element to hold the same in its operative position.

50 3. Locking mechanism for a door mounted to swing to and from a closed position comprising, a bored handle knob mounted on the door, a spring latch element carried by the door and engageable with a fixed abutment to yieldably hold the door closed, a key controlled lock cylinder in the bore of the handle knob, and a locking bolt carried by the lock cylinder and having a part engageable with the spring latch 55 element to hold the same in its operative position and a part engageable directly with the fixed abutment to positively secure the door closed.

60 4. In combination with a hollow door movable to and from a closed position, mechanism to secure the door closed comprising a spring finger mounted within the hollow of the door and projecting therefrom for engagement with a fixed abutment to yieldably hold the door closed, a locking bolt mounted within the hollow of the door and adapted to project therefrom into engagement with the spring finger to secure 70

the same in its operative position, and a key controlled lock cylinder accessible from the exterior of the door to actuate said locking bolt.

5. In combination with a hollow door movable to and from a closed position, mechanism to secure the door closed comprising a spring finger mounted within the hollow of the door and projecting therefrom for engagement with a fixed abutment to yieldably hold the door closed, a locking bolt mounted within the hollow of the door and adapted to project therefrom into engagement with the spring finger to secure the same in its operative position, a key controlled lock cylinder accessible from the exterior of the door to actuate said locking bolt, and common means to mount the spring finger and the lock cylinder on the door. 80

85

90

95

100 6. In combination with a hollow door having an inner and an outer wall and movable to and from a closed position, locking mechanism to secure the door closed comprising a bored handle knob mounted on the outer wall of the door with its inner end portion extending into the hollow of the door, a spring latch element having a part apertured to receive the inward extension of the handle knob and lying flat against the inner face of the outer wall of the door, means to simultaneously hold said spring latch element and the handle knob in position on the outer wall of the door, said spring latch 105 element having a finger projecting from the hollow of the door for engagement with a fixed abutment to secure the door closed, a key operable lock cylinder mounted in the bore of the handle knob, and a locking bolt carried by the 110 lock cylinder with its outer end portion projectable from the hollow of the door into engagement with the spring finger to hold the same in its operative position.

115 7. In combination with a movable member to be secured in a predetermined position, a bored member, a spring latch element having a spring finger engageable with a fixed abutment to yieldably hold said member in said predetermined position, common means to secure said 120 bored member and spring latch element to said movable member, a key operable lock cylinder mounted in the bore of said member, and a locking bolt carried by the lock cylinder and engageable with the same fixed abutment with 125 which the spring finger engages to positively lock said movable member in said predetermined position.

130 8. In combination with a door hinged to swing to and from a closed position, a bored handle knob, a spring latch element comprising a formed piece of spring metal provided with an apertured flat portion engageable over part of said bored handle knob, means to simultaneously secure the handle knob and said spring 135 latch element to the door, said spring latch element having a spring finger projecting therefrom for engagement with a fixed abutment to yieldably hold the door in its closed position, a key operable lock cylinder rotatable in the bore 140 of the handle knob, and a locking bolt carried by said lock cylinder and adapted to swing into engagement with the same fixed abutment with which the spring finger engages to positively 145 hold the door in its closed position.

STEPHEN F. BRIGGS.
